SAFETY DEVICE FOR SHIPS

Martin Petersen, Aberdeen, Wash.

Application May 2, 1935, Serial No. 19,499

3 Claims. (Cl. 114—219)

This invention relates to a safety device for ships and has for the primary object the provision of a device of this character which may be readily rendered operative or inoperative and is preferably placed in operation when a ship is nearing or entering shoal waters and which will give an alarm or signal when the ship reaches waters unsafe due to the depth of the water and will automatically stop engines or other propulsion medium of the ship.

With these and other objects in view, this invention consists in certain novel features of construction, combination and arrangement of parts to be hereinafter more fully described and claimed.

For a complete understanding of my invention, reference is to be had to the following description and accompanying drawings, in which

Figure 1 is a fragmentary side elevation, partly in section, illustrating a ship equipped with a safety device constructed in accordance with my invention.

Figure 2 is a sectional view taken on the line 2—2 of Figure 1.

Figure 3 is a sectional view taken on the line 3—3 of Figure 1.

Referring in detail to the drawings, the numeral 1 indicates a fragmentary portion of a ship, the propulsion medium being indicated by the character 2 controlled by a valve or similar medium 3. The wheel or pilot house is indicated by the character 4. The bow of the ship is indicated by the character 5 and secured to the bottom of the bow portion 5 for pivotal movement is a detector plate 6 hinged upon opposite sides of the keel of the ship, as shown at 7. Struckout portions 8 are formed in the plate to provide water passages therethrough and tapered lips which when engaged by the water passing through the plate act to urge the plate downwardly. Secured to the plate 6 and operating through packing glands 9 are arcuately curved arms 10. The packing glands 9 act as water seals between the arms and the hull of the ship. The upper ends of the arms 10 are disposed within the hull of the ship and have pivotally connected thereto rods 11 slidable through a switch plate 12. Mounted on the rods 11 are coil springs 13 which seat against collars 14 secured to the rods and against seats 15 carried by the switch plate 12. The switch plate is secured to a support, as shown at 17, and is of a flexible material. A switch 18 is carried by the support and when in an open position engages with the switch plate, as clearly shown in Fig-

ure 1. The switch is connected in an electric circuit 19.

Levers 20 are pivotally and slidably connected to the arms 10, as shown at 21, and also are pivoted to the hull of the ship, as shown at 22. The levers 20 are moved in one direction by the action of springs 23, each consisting of a series of leaves and each is pivoted to the hull, as shown at 24, with the free end engaging an adjustable spring seat 25. The spring seats are slidably mounted on the levers and are adjusted and held in adjusted position by mediums 26. A clamp 27 engages the springs and has threaded thereto a feed stem 28 which is threaded to a block 29 pivoted to the hull of the ship. The feed stem provides means whereby the action of the springs on the levers 20 may be varied.

An electric motor 30 has a driving connection with the control medium 3 and is electrically connected in the electric circuit. An electric signal 31 is located in the pilot or wheel house and is electrically connected to the electric circuit and the latter has connected therein fuses 32.

A suitable hoisting mechanism 33 is mounted in the hull of the ship and may be connected and disconnected with the arms 10. Through the hoisting mechanism 33 the detector plate may be moved upwardly to parallel the bottom of the ship and thereby placed in an inoperative position. The arms 10 when freed of the hoisting mechanism will be urged by the springs 27 to move outwardly of the ship, positioning the detector plate 6, as shown in Figure 1.

The device as shown in Figure 1 is rendered operative and when the ship reaches waters that are unsafe, the detector plate will engage with the bottom of the water, causing an upward pivotal movement thereof, moving therewith the arms 10 bringing about the closing of the circuit by the switch 18. The electric motor 30 closes the control medium 3, stopping the propulsion medium of the ship, also the circuit being closed by the switch actuates the signal or alarm 31 in the pilot or wheel house. As soon as the ship is navigated from the shallow waters the springs 27 act to position the detector plate 26 into operative position, as shown in Figure 1.

Having described the invention, I claim:

1. A safety device for ships comprising a detector plate hinged to the bottom of the ship and having a series of struckout portions forming openings to said plate and tapered tines to be acted on by the water for urging the plate downwardly from the ship, and operating means connected to said plate and extending into the ship,

- an electric switch actuated by said means, an electric circuit controlled by said switch, and electrical means connected to said circuit for giving a signal and for controlling the propulsion medium of the ship.
2. A safety device for ships comprising a detector plate hinged to the bottom of the ship, arcuately curved arms secured to said plate and extending into the interior of the ship, stuffing boxes between the ship and the arms, a switch operating means connected to the arms, a switch controlled by said switch operating means, electrical means connected to said switch and to an electric circuit, levers pivoted to the ship and pivotally and slidably connected to the arms, and spring means acting upon said levers to urge the detector plate into operative position.
- 10
- 15

3. A safety device for ships comprising a detector plate hinged to the bottom of the ship, arcuately curved arms secured to said plate and extending into the interior of the ship, stuffing boxes between the ship and the arms, a switch operating means connected to the arms, a switch controlled by said switch operating means, electrical means connected to said switch and to an electric circuit, levers pivoted to the ship and pivotally and slidably connected to the arms, 5 spring means acting upon said levers to urge the detector plate into operative position, and means carried by the ship and connectible to the arms for holding the detector plate in an inoperative 10 position.

MARTIN PETERSEN.
